UNITED STATES PATENT OFFICE

161,024

AUTOMOTIVE VEHICLE

Ivey Herpin, Dallas, Tex.

Application February 4, 1949, Serial No. 676

Term of patent 7 years

(Cl. D14—3)

To all whom it may concern:

Be it known that I, Ivey Herpin, a citizen of the United States of America, residing at Dallas, in the county of Dallas and State of Texas, have invented a new, original, and ornamental Design for an Automotive Vehicle, of which the following is a specification, reference being had to the accompanying drawing, forming part thereof.

In the drawing:

Fig. 1 is an elevational view of an automotive vehicle, showing my new design;

Fig. 2 is a plan view, seen from above, of the vehicle shown in Fig. 1.

Fig. 3 is a rear elevational view of the vehicle.

Fig. 4 is the front elevational view of the vehicle.

I claim:

The ornamental design for an automotive vehicle, as shown.

IVEY HERPIN.
